UNITED STATES PATENT OFFICE.

EDWIN M. BURROUGHS, OF DETROIT, MICHIGAN.

SOAPSDS AND HOT-WATER DISPENSER.

1,077,590.

Specification of Letters Patent.

Patented Nov. 4, 1913.

Application filed April 18, 1913. Serial No. 761,881.

To all whom it may concern:

Be it known that I, EDWIN M. BURROUGHS, citizen of the United States, residing at Detroit, county of Wayne, State of Michigan, have invented a certain new and useful Improvement in Soapsuds and Hot-Water Dispensers, and declare the following to be a full, clear, and exact description of the same, such as will enable others skilled in the art to which it pertains to make and use the same, reference being had to the accompanying drawings, which form a part of this specification.

My invention relates to an attachment for hot water faucets adapted to dispense either hot water or soap suds as shown in the accompanying drawings and more particularly set forth in the following specification and claims.

The object of my invention is to provide a device which may be readily attached to a hot water faucet without altering the plumbing or injuring the fixtures and by means of which either clear water or soap suds may be dispensed as required.

Other advantages and improvements will hereafter appear.

In the drawings accompanying this specification:—Figure 1 is a side elevation of the device attached to a hot water faucet and provided with a hose connection for leading the suds away to any point desired. Fig. 2 is a vertical cross-sectional view through the device. Fig. 3 is a cross-sectional view through the closure cap at right angles to Fig. 2, showing in dotted lines the spigot-valve adjusted so that the water may pass through the soap cup.

Referring now to the letters of reference placed upon the drawings, A indicates a hot water faucet. B a suds dispensing device consisting of a cup C to receive and house scraps of soap (not shown) and a closure cap D having a screw-threaded engagement with the cup. The cup is provided with an upstanding annular neck D' in which is fitted a rotatable spigot-valve E, having a port E' through which clear water may be discharged from the faucet A without passing through the soap cup by rotating the spigot so that the port E' may register with the port d in the neck D'. The spigot-valve is of tapering construction, the joint being preferably ground into the upstanding neck D' that it may not leak around the spigot. The end of the spigot-

valve is fitted with a split washer e, one face of which bears against the wall of the upstanding neck, the other being engaged by the head of a screw e',—fitted in the end of 60 the spigot,—upon adjusting which any end play may be taken up.

D² is an annular bushing adapted to slip over the end of the faucet A, and D³ is a flanged nut for supporting the bushing, having a screw-threaded engagement with the upper end of the neck D'. The device is suspended from the faucet A by a chain A', one end of which is secured to an ear a, projecting from the neck D'. The chain A' is 70 looped around the body of the faucet its free end being hooked over a pin a' extending from the neck D' on the opposite side from the ear a.

E² is a port through the spigot-valve designed to register with the discharge port d' whereby hot water may pass from the faucet A into the cup C through the discharge ports d² in the cap.

G is a rotating paddle blade supported on 80 the stub shaft g suspended from the cap D.

H is a screen spaced from the bottom wall of the cup upon which scrap pieces of soap (not shown) may rest.

C' is an annular screw-threaded nipple 85 projecting from the bottom of the soap cup to receive a suitable fitting I, connected with a hose I', which in turn may be provided with a suitable rose or spray nozzle I², through which the soap suds may be discharged. 90

Having indicated the several parts by reference letters, the construction and operation of the device will be readily understood.

The device is suspended from the hot water faucet by means of the chain, as indicated in Fig. 1, the rubber gasket slipping over the discharge neck of the faucet. The cup portion is then disconnected from 100 the closure cap and charged with scraps of soap; the cup is then reengaged and the hot water turned on.

If clear hot water is desired the spigot-valve is turned so that its discharge port 105 registers with the port d as indicated in Fig. 2, in which case the clear water will pass out without going through the cup. When soap suds are desired the spigot-valve is turned to cause the port E² to register with the port d'; hot water now passes into and through 110 the cup and upon impinging with the paddle

blades G, the latter are caused to rotate thereby churning the water and forming soap suds which pass out through the discharge port C' and hose I'.

- 5 By the employment of this device any desired quantity of hot creamy soap suds may be had for washing dishes, floors, etc., or the device may be attached to the bath room fixtures for shampoo or baths. The suds 10 may easily be washed away by merely turning the spigot-valve thereby providing, in place of suds, clear hot water.

Having thus described my invention, what I claim is:—

- 15 1. In a device of the character described, a cup to receive soap, a closure cap for the cup fitted with a valve to admit water into the cup or to discharge it outside of the cup without passing through the cup, and a revolving paddle housed within the cup adapted to be actuated by the water passing through the cup, whereby the water may be churned within the cup while passing through it.
- 20 2. In a device of the character described, a cup to contain soap provided with a discharge port below, a removable closure cap having an upstanding annular neck to receive the end of a faucet, an annular gasket 25 carried by the neck to receive the faucet

whereby a water tight connection between the same may be obtained, a revolving paddle housed within the cup actuated by the water and to churn the water as it passes through the cup, and a chain engaging the device adapted to be looped around the faucet to suspend it therefrom.

35

3. In a device of the character described, a cup provided with a discharge orifice below, a screen fitted within the cup above the discharge orifice to support soap and to arrest its discharge through the orifice, a removable closure cap having an upstanding annular neck to receive the end of a faucet, an annular gasket carried by the neck to receive the faucet whereby a water tight connection between the same may be obtained, a revolving paddle housed within the cup actuated by the water and to churn the water as it passes through the cup, and a chain engaging the device adapted to be looped around the faucet to suspend it therefrom.

40

45

In testimony whereof, I sign this specification in the presence of two witnesses.

EDWIN M. BURROUGHS.
